UNITED STATES PATENT OFFICE.

JOSEPH M. NOEL, OF PORTAGE, PENNSYLVANIA.

GASOLENE-TANK FILLER.

1,281,815.

Specification of Letters Patent. Patented Oct. 15, 1918.

Application filed August 10, 1917. Serial No. 125,579.

To all whom it may concern:

Be it known that I, JOSEPH M. NOEL, a citizen of the United States, residing at Portage, in the county of Cambria and State of Pennsylvania, have invented a new and useful Gasolene-Tank Filler, of which the following is a specification.

This invention relates to a filler for gasolene tanks, one of its objects being to provide means whereby a gasolene tank located under a seat of an automobile can be filled without removing the seat cushion.

A further object is to combine with a filler a gage which can be collapsed so as to occupy the minimum space, said gage being concealed within the filler.

Another object is to provide a filler which allows for the admission and escape of air during the emptying and filling of the tank respectively.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:

Figure 1 is a vertical section through a portion of a tank and seat having the present improvements combined therewith.

Fig. 2 is a detail view of the gage.

Fig. 3 is a horizontal section through the tube of the filler.

Referring to the figures by characters of reference 1 designates the tank for holding gasolene and arranged directly above this tank is an ordinary spring cushion 2 constituting a seat. Extending through the cushion is a filling tube 3 having an annular flange 4 at its upper end. The lower end of this tube is rounded to slide through a cup 5 secured within the top of the tank 1 and which cup contains superposed washers 6 and 7 which may be formed of fiber and felt respectively or of any suitable material. These washers fit snugly about the tube 3 and are held in the cup by a removable cap 8. Thus it will be seen that the tube 3 is

capable of moving vertically through the cup.

The flange 4 rests upon and may be suitably secured to the top of the seat cushion. This flange, however, is covered by a button 9 which can be formed of leather or other flexible material and which is secured upon a plug 10 insertible into the upper end of the tube 3. Secured to this plug is the upper end of a folding rule 11 constituting a gasolene gage. This rule is normally folded up into the tube and, therefore, will not interfere with the vertical movement of the tube within the top of the tank.

It will be apparent that under ordinary conditions the occupant of the seat 2 can sit on the button 9 which, furthermore, will entirely conceal the tube. When it is desired to fill the tank it is merely necessary to remove the button 9 and plug 10 whereupon the gasolene can be poured into the tube 3 and will flow into the tank. The gage rule 11 can be unfolded and used to determine the amount of gasolene in the tank. After the tank has been filled the gage can be folded and inserted into the tube 3, the plug 10 completely closing the upper end of the tube and the button 9 fitting snugly over the flange 4. Obviously the plug 10 can be held in place by friction or it can be provided with a coarse thread so that by turning the plug it will screw into the tube and be securely held.

What is claimed is:

1. The combination with a gasolene tank and a yielding seat supported thereabove, of a tube secured to the top of the seat and extending downwardly therethrough, said tube projecting into and being slidable within the top of the tank, and a plug closing the upper end of the tube.

2. The combination with a gasolene tank and a yielding seat supported thereabove, of a tube secured to the top of the seat and extending downwardly therethrough, said tube projecting into and being slidable within the top of the tank, and a plug closing the upper end of the tube, said plug having a covering constituting a finishing material for concealing the upper end of the tube.

3. The combination with a gasolene tank and a yielding cushion thereabove, of a tube having a flanged upper end secured to the top of the cushion, said tube extending

downwardly through the cushion and being
slidably mounted in the top of the tank, a
plug for closing the upper end of the tube,
a finishing material carried by the plug
and extending over the flange on the tube to
conceal the flange, and packing material car-
ried by the tank and embracing the tube.

In testimony that I claim the foregoing
as my own I have hereto affixed my signa-
ture in the presence of two witnesses.

JOSEPH M. NOEL.
